INVENTOR

William A. Gore

Patented Oct. 12, 1926.

UNITED STATES PATENT OFFICE.

WILLIAM A. GORE, OF WEBSTER GROVES, MISSOURI.

EDUCATIONAL TOY BUILDING BLOCK.

Application filed November 23, 1923. Serial No. 676,511.

My invention relates to improvements in educational toy building blocks, some faces of which are designed or marked with stripes along their margins; and the objects of my improvement are first, to provide a suitable medium in the nature of building blocks, made preferably of wood or other light material, for educational and recreational use by children in the solution of practical problems in buildings and construction; second, to give to this material greater educational value by designing certain faces of the blocks in such manner as to require the careful thinking of the builder in correctly and properly assembling the blocks in such manner that the designs on the faces of the individual blocks will contribute properly to the effect of the assembled collection or structure as a whole; third, to cause the blocks when a number of them are properly assembled and laid together in rows or courses one upon another to present the appearance, because of the mortar-imitating stripes on the margins of some of the faces, of brick, tile, stone or other similar building material laid together in mortar or cement.

Figure 1 is a perspective view of a block designed for use in building plain walls and corners and embodies the features of my invention. Figure 2 is a perspective view of a block designed for use in building corners, columns and pilasters and embodies the features of my invention. Figure 3 is a perspective view of a number of blocks properly assembled in courses laid one upon another forming a wall and corner. Figure 4 is a perspective view of a number of blocks properly assembled forming a column.

In Figure 1, *a* is a mortar-imitating stripe along the lower margin on an end of the block; *b* is a mortar-imitating stripe extending from an end of *a* along the lower edge of the front face of the block and connecting with *c*, which is a vertical mortar-imitating stripe along the right margin of the same face. Stripes *b* and *c* form an L-shaped figure extending the entire length of two adjacent margins of the front face of the block.

In Figure 2, *d* is a mortar-imitating stripe along the lower edge of the left end of the block; *e* is a mortar-imitating stripe extending along the lower edge of the front face of the block, connecting at the left end with *d* and at the right end with *f*, which is a mortar-imitating stripe extending along the lower margin of the right end of the block, from the right end of *e* to *g*, which is a vertical mortar-imitating stripe extending from *f* along the back margin of the right end of the block. Stripes *f* and *g* form an L-shaped figure extending the entire length of two adjacent margins of the right end of the block.

In Figure 3 a number of blocks are so assembled that with reference to the portions of each block that are exposed to view the mortar-imitating stripes thereon occupy the same relative positions, giving to the entire assembled collection the appearance of a structure of brick, tile, stone or other similar building material laid in mortar or cement.

In Figure 4 a number of blocks of the type shown in Figure 2 are so assembled that the blocks are all in the same relative position, the mortar-imitating stripes extending along the entire lower margins of the front face and both ends of the blocks and in a vertical position along the right margin of the right end of each block.

I claim:—

1. A toy building block provided with horizontal mortar-imitating stripes along the lower margins of its exposed surfaces, and a mortar-imitating stripe extending upwardly from the extremity of one of said first-named stripes along the margin of one face of the block.

2. A toy building block having upper and lower horizontal faces and vertical exposed faces and provided with mortar-imitating stripes along the margins of the exposed faces adjacent to one of the horizontal faces, and provided with a mortar-imitating stripe extending upwardly from the end of one of said first-named stripes and on the same exposed face of the building block.

3. A toy building block provided with a mortar-imitating stripe on only one of the

longitudinal margins of its front face, and a mortar-imitating stripe on only one of the end margins of said face.

4. A toy building block with a mortar-imitating stripe extending the entire length of the lower longitudinal margin of its front face; a second mortar-imitating stripe extending backward from the left extremity of the first stripe along the lower margin of the left end of the block;

and a third mortar-imitating stripe extending upward from the right extremity of the first stripe along the right margin of the front face of the block; the third stripe, together with the first, forming an L-shaped design or figure covering two adjacent margins of the front face of the block.¹⁵

WILLIAM A. GORE.
